(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the delineated portion 8 in FIG. 1;

FIG. 9 is an enlarged view of the delineated portion 9 in FIG. 2;

FIG. 10 is an enlarged view of the delineated portion 10 in FIG. 4;

FIG. 11 is a front perspective view of the electronic device of FIGS. 1-10 showing the electronic device in an open position;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is an enlarged view of the delineated portion 18 in FIG. 11; and,

FIG. 19 is an enlarged view of the delineated portion 19 in FIG. 14.

The dashed broken lines in the figures illustrate portions of the electronic device that form no part of the claimed design.

(Continued)

The dot-dash broken lines in the figures delineating portions of the claimed design that are shown in enlargements form no part of the claimed design.

1 Claim, 19 Drawing Sheets
